UNITED STATES PATENT OFFICE.

THEODORE R. TREIBER, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

GAME-TABLE.

1,237,417.

Specification of Letters Patent. Patented Aug. 21, 1917.

Application filed November 1, 1916. Serial No. 128,900.

To all whom it may concern:

Be it known that I, THEODORE R. TREIBER, a citizen of the United States, residing at Chicago, in the county of Cook and State of Illinois, have invented certain new and useful Improvements in Game-Tables, of which the following is a specification:

This invention relates in general to billiard and other game tables and more particularly to tables constructed of metal.

It is the object of my invention to provide a table, the body of which is constructed entirely of metal, the ornamental portions being readily separable from the structural or supporting portions.

A further object of my invention is the provision of a table which may be quickly knocked down and as readily assembled.

A further object of my invention is the provision of means whereby the top of the table may be leveled without lifting the legs from the surface on which they normally rest.

Further objects and advantages of my invention will be apparent as it is better understood by reference to the following specification when read in connection with the accompanying drawing, illustrating the preferred embodiment thereof, in which—

Figure 1 is a view in perspective of a portion of a game table according to my invention;

Fig. 2 is a view in perspective of one of the legs removed from the table;

Fig. 3 is a view in perspective of the supporting portion of the leg illustrated in Fig. 2;

Fig. 4 is a view in perspective of one of the facier plates;

Fig. 5 is a plan view, partially in section, of a portion of a table with the top removed;

Fig. 6 is a vertical section on the line 6—6 of Fig. 5;

Fig. 7 is an enlarged detail in section illustrating the mode of adjusting the frame with respect to the legs, and

Fig. 8 is a horizontal section on the line 8—8 of Fig. 7.

Referring to the drawing the table is illustrated as consisting of a top of usual construction embodying the rails 1, a cushion 2, bed 3 and cloth 4. The bed 3 is supported upon a frame consisting of longitudinally and transversely extending chan-

nel members 5 and 6 connected as illustrated in Fig. 8 by removing the flanges of the channels, bending the webs 7 and fastening by means of bolts 8. A diagonal channel 9 and channels 9' and 10' secured by said bolts brace the frame and give it sufficient rigidity.

The supporting portions of the legs (Fig. 3) comprise plates 11 bent to provide feet 12 upon which the supporting plate 13 rests and to which it is secured by suitable rivets 14. A plate 15 is bent as indicated in Fig. 3 and is secured in position by braces 16 fastened to the plates 11 and 15 by rivets 17 and 18. Threaded openings 19 are provided in the plates 15 and braces 16, the purpose of which will more fully appear hereafter.

The ornamental portion of the legs comprises a shell 20, preferably of sheet metal, and formed in any desirable ornamental style, as indicated in Fig. 1. The shell 20 is bent to form a groove 21 adapted to receive the edges of the plate 15 when the supporting portion of the leg is disposed within the shell 20. The shell 20 is also bent to form a groove 22 adapted to receive the ends of the facier plates 23 when the table is assembled, the facier plates being slightly shorter than the distance between the bottoms of the grooves 22 on adjacent legs so that the facier plates may be readily positioned. The facier plates 23 comprise plates preferably of sheet metal flanged at 24 and 25 to give the table a finished appearance when assembled.

The channels 5 and 6 are provided adjacent the corners and middle of the frame with the slots 26 (Fig. 7) adapted to receive bolts 27 which engage the threaded openings 19 in the plates 15 and the braces 16. When the legs are assembled the frame may be readily leveled by adjusting the legs with respect thereto, the bolts 27 operating in the slots 26, and thereafter tightening the bolts to retain the legs in adjusted position. It will be seen that it becomes possible by the use of my invention to level the frame and consequently the bed 3 without raising either of the legs above the floor or support upon which it is intended to rest.

When the supporting portions of the legs have been assembled with the frame in the manner described the ornamental shells 20 are slipped over the legs and the facier plates 110

23 are inserted in the grooves 22 in which position they are clamped by the screws 28 (Fig. 8) which pass through the channels 5 and 6 and force the facier plates 23 outward against the sides of the grooves 22. The bed 3 may then be secured upon the frame and the table is ready for use.

From the foregoing it will be readily understood that I have succeeded in perfecting a metal table which may be readily assembled from standard and interchangeable parts and the ornamental portions of which may be varied within a wide range, it being possible to stamp the shells forming the decorative portions of the legs with various designs and the entire table being susceptible to receive finishes of differing character, depending upon the taste of the prospective user. Moreover, my improved table is of a minimum weight consistent with sufficient strength and particularly the rigidity which is essential to a game table of this character. The provision of means for adjusting the frame with respect to the legs does away with an annoying feature of tables of the usual form which require one or more of the legs to be supported on blocks where the surface upon which the table rests is uneven.

30 It will be further understood that various changes may be made in the form, construction and arrangement of the parts without departing from the spirit and scope of the invention or sacrificing any of its material advantages, the form hereinbefore described being merely a preferred embodiment thereof.

I claim:

1. In a game table, the combination of a metal frame, metal legs, each comprising a supporting portion and a seat to receive a section of said frame, and means for adjustably securing said legs to said frame.

2. In a game table, the combination of a metal frame, metal legs, each comprising a supporting portion and a seat to receive a section of said frame, elongated openings in said frame, and bolts disposed in said openings and threadedly engaging said legs to adjustably secure said legs to said frame.

3. In a game table, the combination of a metal frame, metal legs adjustably secured thereto, and ornamental metal shells surrounding said legs.

55 4. In a game table, the combination of a

metal frame, metal legs adjustably secured thereto, ornamental metal shells surrounding said legs, and facier plates covering said frame between said legs.

5. In a game table, the combination of a metal frame, metal legs adjustably secured thereto, ornamental metal shells surrounding said legs, facier plates removably disposed between said legs, and means for securing said facier plates in position. 60

6. In a game table, the combination of a metal frame, legs comprising metal upright members, and a horizontal metal plate secured to said upright members and forming therewith a seat to receive said frame and means for adjustably securing said legs to said frame. 70

7. In a game table, the combination of a metal frame, legs comprising metal upright members, a horizontal metal plate secured to said upright members and forming therewith a seat to receive said frame, and means for adjustably securing said legs to said frame, and ornamental metal shells surrounding said legs. 75

8. In a game table, the combination of a metal frame and legs secured thereto comprising metal upright members, a horizontal metal plate secured to said upright members and forming therewith a seat to receive said frame, ornamental metal shells surrounding said legs, and facier plates covering said frame between said shells. 80

9. In a game table, the combination of a frame and supporting means therefor of structural metal, metal shells surrounding said supporting means and provided with grooves, facier plates disposed between said shells with their ends in said grooves, and means for securing said facier plates in position. 90

10. In a game table, the combination of a frame and supporting means therefor of structural metal, metal shells surrounding said supporting means and provided with grooves, facier plates disposed between said shells with their ends in said grooves, and screws in said frame engaging the inner faces of said facier plates to secure them in position. 100

THEODORE R. TREIBER.
